UNITED STATES PATENT OFFICE.

BENJAMIN V. GILMORE, OF RED HOUSE SHOALS, WEST VIRGINIA.

MINING-DRILL.

No. 831,056.

Specification of Letters Patent.

Patented Sept. 18, 1906.

Application filed February 14, 1906. Serial No. 301,109.

To all whom it may concern:

Be it known that I, BENJAMIN V. GILMORE, a citizen of the United States, residing at Red House Shoals, in the county of Putnam and State of West Virginia, have invented certain new and useful Improvements in Mining-Drills, of which the following is a specification.

This invention relates to boring-tools for mining operations, being designed most especially for cutting into coal to prepare openings for reception of the explosive.

The invention consists of a tool of novel formation of the type comprising a hollow body provided upon its exterior with a spiral clearer to carry off the cuttings and having openings in its side for escape of the inner cuttings and provided with an exterior cutter to insure separation of the core at or near its base prior to removal of the tool after the bore 20 has reached the required depth.

An essential feature of the invention resides in the peculiar arrangement of the core and cutter with reference to the body of the tool and in the mounting for said cutter and 25 in the means for preventing displacement of the mounting.

The invention further resides in the novel structure of the tool, whereby its efficiency is enhanced and the operation of the boring facilitated, the toothed portion being removable, so as to be readily replaced at a nominal cost when dull or otherwise rendered unfit for further effective service.

The invention also consists of the novel features which hereinafter will be more particularly set forth, illustrated, and finally claimed.

In the accompanying drawings, forming part of the specification, Figure 1 is a perspective view of the end portion of a tool embodying the invention provided with the cutting-teeth. Fig. 2 is a central longitudinal section of the cutting-end portion of the tool. Fig. 3 is a transverse section on the line xx of Fig. 2.

Corresponding and like parts are referred to in the following description and indicated in all the views of the drawings by the same reference characters.

The body 1 of the tool is hollow or tubular and is thickened near its cutting end, as shown at 2, and is provided upon its exterior with a spiral flight or clearer 3, preferably of a width corresponding to the extra thickness 2 at or near the cutting end of said body. The flight 3 may consist of a ribbed flange or like

part either formed with the body 1 as a part thereof or welded, brazed or otherwise secured thereto as a separate part. The purpose of the flight or clearer 3 is to carry off 60 cuttings resulting from the operation of the tool when in service. A series of openings 5 are formed in the body 1 between the flight or clearer 3 and provides an escape for the inner cuttings, thereby preventing binding between the core of the inner walls of the tool when the latter is performing work. The openings 5 are located between the volutes of the flight, so as not to interfere with the latter in any manner.

The cutters 6 are swaged, so as to project beyond the inner and outer walls of the thickened end portion of the tool, and thereby provide ample clearance therefor. The cutters 6 are in the form of teeth and form part of a 75 ring 7, which is fitted to the cutter end of the tool and tempered so as to resist the dulling action of the mineral while the tool is in operation. It is preferred to have the ring 7 connected with the body 1 by means of a 80 screw-threaded joint 8, and for this purpose the cutter end of the tool is reduced and exteriorly threaded, and the attaching end of the ring 7 is enlarged and interiorly threaded to match the reduced threaded end of the 85 body 1, as shown most clearly in Fig. 2, the thread being such as to prevent loosening of the ring when rotating the tool and advancing the same into the mineral in the mining operation.

A cutter 9 is located near the cutting end of the tool and projects from the inner wall thereof so as to cut into the core formed by the tool. The cutter 9 preferably consists of a wheel or disk and is arranged in an opening 95 or recess 10 formed in the thickened portion 2 and is preferably set angling, so as to correspond approximately with the pitch of the flight or clearer 3. The rotary cutter 9 is mounted upon a pin 11, which is let into an 100 opening 12, formed in the thickened portion 2, said pin being supported at its ends upon opposite sides of the opening or recess 10 and held in place by the cutter-ring 7, as indicated most clearly in Fig. 2.

The tool is adapted to be rotated in any manner well understood in mining operations and being of hollow or tubular form makes a cylindrical cut, the core entering the body 1. The cutter 9 materially assists in the 110 feed or advancement of the tool by reason of its cutting into the core in a spiral direction,

the cuttings formed thereby finding a ready escape through the openings 5 to the exterior of the tool, so as to be carried off by means of the clearer 3. When the cutter has reached 5 the requisite depth, the tool is held from further advancement, thereby forming an annular groove or cut at the inner end of the core, thereby severing said core or admitting of the same being readily broken off when withdrawing the tool, thereby providing an opening for the reception of cartridge or other explosive employed for loosening and dislodging the mineral or other substance.

Having thus described the invention, what 15 is claimed as new is—

1. A hollow or tubular mining-tool, a cutter detachably fitted to an end thereof, an inner cutter and a pin for securing the inner cutter in place and in turn prevented from 20 displacement by the said removable end cutter.

2. A hollow or tubular mining-tool provided with a thickened end having a reduced and threaded terminal portion and provided with an exterior spirally-arranged clearer and 25 having openings in its sides between the volutes of said clearer, a rotary cutter let into an opening or recess in the thickened end portion of the body and projected into the space of the body from its inner wall, a pin supporting the rotary cutter and let into an opening formed in the thickened end portion of the tool, and a ring provided with teeth and connected by a screw-threaded joint provided with the reduced terminal portion of the tool- 30 body.

In testimony whereof I affix my signature in presence of two witnesses.

BENJAMIN V. GILMORE. [L. S.]
